CLAIM

The ornamental design for a sports game, as shown and described.

DESCRIPTION

FIG. 1 is a perspective view of a sports game showing my new design;

FIG. 2 is a top plan view thereof;

FIG. 3 is a bottom plan view thereof;

FIG. 4 is a front elevation view thereof, the rear being a mirror image thereof;

FIG. 5 is a left-side elevation view thereof; and,

FIG. 6 is a right-side elevation view thereof.

The broken lines are included to show features of the sports game that form no part of the claimed design.
